United States Patent Office

Des. 210,630
Patented Mar. 26, 1968

210,630

DOCUMENT REPRODUCING APPARATUS

Jacob W. Patla, Rochester, N.Y., assignor to Xerox
Corporation, Rochester, N.Y., a corporation of
New York

Filed Oct. 13, 1966, Ser. No. 4,261

Term of patent 14 years

(Cl. D61—1)

FIG. 1

FIG. 2

FIG. 3

FIG. 4

FIG. 5

FIG. 1 is a left side, top and front perspective view of a document reproducing apparatus, showing my new design;

FIG. 2 is a front elevational view;

FIG. 3 is a right side elevational view;

FIG. 4 is a fragmentary left side elevational view, a portion being broken away for convenience in illustration; and

FIG. 5 is a top plan view thereof.

I claim:

The ornamental design for a document reproducing apparatus, as shown.
